Attorney.

UNITED STATES PATENT OFFICE.

JOHN JAMES BURKE COLE AND AILLEEN CHARLOTTE COLE, OF HUNTERFORD,
ENGLAND.

RECEPTACLE FOR USE BY SMOKERS FOR TOBACCO ASH AND THE LIKE.

Application filed January 7, 1927, Serial No. 159,664, and in Great Britain January 25, 1926.

This invention relates to a novel and convenient construction of pocket match-box, cigarette lighter, or cigarette case, combined with a receptacle for tobacco ash. Particularly the invention relates to pocket ashtrays combined with match-boxes or containers of the kind comprising a casing to which the match-box or container is hinged and into which it can be folded.

According to the present invention a match-box consisting of a box-like receptacle for matches having a lid, slide, or closing flap, or a cigarette lighter, or a cigarette case, formed as a unit is hinged at one end to a casing into which it can be folded, the said casing, when the match-box, lighter or cigarette case is raised, constituting an ashtray and having an ash discharge opening controlled by a lid or closure that is independent of the match-box, lighter or cigarette case unit. By providing the match-box with a lid, slide, or closing flap the matches are protected when the said lid or closing member is closed in addition to the protection obtained by folding the box down into the casing to which it is hinged. The ash discharge opening in the casing is preferably at the opposite end of the casing to that at which the match-box or lighter is hinged and the said discharge opening is closed by a hinged lid, or slide, formed it may be as a receptacle for tobacco ash. Conveniently the upper wall of the ash receptacle, when the said lid or slide is formed as an ash receptacle, has formed in it a depression that constitutes a rest for a cigarette or cigar. In cases where a simple flap or slide is provided to close the ash discharge opening, a groove to form a cigarette or cigar rest may be formed in a wall of the match-box, lighter, or cigarette case.

Figs. 1, 2 and 3 of the accompanying drawings show in side elevation, end elevation, and plan, respectively, a combined match-box and ash receptacle according to the invention.

Figs. 4 and 5 are similar views to Figs. 1 and 3 respectively but showing the match-box in its open position.

Fig. 6 is a cross-section, taken on line 6-6 in Fig. 5.

1 indicates a flat box or case of substantially rectangular shape which is open at the top and to an end wall of which there

is hinged at 2 a match container 3 in the form of a rectangular box furnished with a lid 4. The lid 4 is connected to the match-box 3 by a hinge 5 which, in known manner, embodies a spring that constantly tends to move the lid into the open position indicated in Fig. 4. In order to hold the lid closed against the action of its spring hinge there is pivoted at 6 to the end wall of the match-box a flap 7 the upper edge of which is formed with a bead 8 adapted to engage the free end of the lid 4. The bead 8 does not extend entirely across the width of the lid 3, but for the sake of appearance the portions of said edge at each side of the clip bead 8 are formed with beads 9 corresponding to and in line with the said clip head. The outer face of the flap 7 is suitably formed or provided with a roughened or otherwise treated surface on which matches can be struck, and the hinge 6 of the flap also embodies a spring tending to maintain the flap in a vertical position engaging the edge of the lid 4.

The size of the match box is such that it exactly fits within the box or case 1 when turned down into the closed position shown in Figs. 1 and 3 and in this position the matches are protected against wet and the article is in compact form convenient for carrying say in a waistcoat pocket or lady's bag. When the match box is turned into position for use, shown in Figs. 4 and 5, the box or case 1 constitutes a convenient receptacle for cigarette or cigar ash and hinged at 10 to the lower edge of the front wall 1^a of the box or case 1 is a lid in the form of a pocket 11, of semi-circular shape in plan, into which ash deposited in the box or case 1 can be delivered through openings 12 formed in the front wall of the box or case 1. The hinge 10 also embodies a spring constantly tending to maintain the pocket 11 in the position shown in Figs. 1, 2 and 3, in line with the box or case 1, in which position, moreover, it can be retained by a flap 13 hinged to the box or case 1 and formed with a hole adapted to engage a pin 14 projecting from the pocket 11. In the top wall of the ash pocket 11 and the top edge of the front wall of the box or case 1 a groove 15 is formed in which a cigarette can rest conveniently.

According to a modification instead of the match-box 3 a cigarette lighter of known

character, or a cigarette case, can be hinged to the box or case 1 in like manner to the said match-box 3.

The article constructed as described is convenient in that the ash can be retained in the pocket 11 until it is convenient to discharge the same but if a simple hinged flap, slide, or the like is provided in place of the pocket it is necessary to empty the ash as by blowing it through the ash discharge openings 12 before folding the match-box down into the casing. In such a construction a slight groove, like the groove 15, would preferably be made in the lid 4 of the match-box, or cigarette case, or in the equivalent wall of the lighter, as the case may be.

Whilst in the construction illustrated the ash discharge opening is at one end of the box or case, it will be appreciated that the invention is not restricted to the opening being in such position; it could be at either side or at the bottom of the casing. In some constructions the dimensions of the box or case could be such as to provide a space all round the match-box, lighter, or cigarette case when closed, but such a construction has the disadvantage of increasing the overall size of the article. Furthermore, in some cases the casing might be made in one piece with the pocket 11, and the pocket could then be emptied by the whole underside being lowered on a hinge immediately beneath the hinge 2, Fig. 2, or at the hinge 2, or the under part of the pocket only might drop at the hinge 10, Fig. 1. In both these cases a suitable catch or equivalent would be provided whereby the hinged under part could be held to the casing when closed.

If desired one or more articles of utility might be combined with an ashtray such as described. For instance a mirror might be provided which could conveniently be mounted on the outer or inner side of the match-

box, lighter or cigarette case, or on the bottom or underside of the casing. Similarly the 45 outerside of the lid or the underside of the casing or ashtray might be formed as, or provided with means to constitute, a holder for papier poudre, a memorandum tablet, or the like. 50

If desired the article may have an appropriate clip hinged or otherwise articulated to its underside whereby it may be readily attached to any suitable support, the said clip when not in use lying flat against the said underside. In some cases, if so desired, the ashtray or ash receiving casing can be fitted with a readily removable lining. 55

What we claim is:—

1. A receptacle for use by smokers, comprising an open-topped container for ash provided with a discharge opening, a match box provided with a lid and hinged to the ash container, said match box being foldable into the ash container, and a storage pocket for the ash hinged to the ash container and provided with an opening which communicates with the said discharge opening. 60

2. A receptacle as set forth in claim 1, the match box being hinged to one side of the ash container, and the said pocket being hinged to the opposite side of the ash container. 70

3. A receptacle as set forth in claim 1, the storage pocket being provided with a disengageable spring catch which holds it in the 75 same plane as the ash container to permit the ash to be emptied from the container into the pocket.

4. A receptacle as set forth in claim 1, the said pocket being provided with a depression 80 in its top side for holding a cigarette.

In testimony whereof we affix our signatures.

JOHN JAMES BURKE COLE.
AILLEEN CHARLOTTE COLE.
